Primary Examiner — Holly E Thurman*Assistant Examiner* — Kristopher Michael Blechschmidt(74) *Attorney, Agent, or Firm* — Philip Oweimrin(57) **CLAIM**

The ornamental design for an anti-bird roosting device, as shown and described.

DESCRIPTION

FIG. 1 is a front perspective view of an anti-bird roosting device, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the anti-bird roosting device, which form no part of the claimed design.

The dash-dot broken lines in FIG. 1 & FIG. 9 depict the extent of the enlarged view and forms no part of the claimed design.
